UNITED STATES PATENT OFFICE.

ABRAHAM ANDERSON, OF GALESBURG, ILLINOIS, ASSIGNOR TO THE G. D. COLTON & COMPANY, OF SAME PLACE.

AUTOMATIC CHECK-ROW CORN-PLANTER.

SPECIFICATION forming part of Letters Patent No. 516,177, dated March 13, 1894.

Application filed February 10, 1892. Serial No. 420,960. (No model.)

To all whom it may concern:

Be it known that I, ABRAHAM ANDERSON, a citizen of the United States, residing at Galesburg, in the county of Knox and State of Illinois, have invented certain new and useful 5 Improvements in Check-Rower Corn-Planters, of which the following is specification.

This invention relates generally to check rower corn planters, of that class or type in which the dropping mechanism of the planter is actuated at uniform distances in the travel of the planter, for depositing the seed in check rows, by contact of a forked lever or arm of the check rower rock shaft with tappets located in regular sequence on a check rower line which is laid over the ground adjacent to the path of the planter, and which contact trips or swings the forked lever, and thereby gives a partial rotation in one direction to the rock shaft, a motion in a reverse direction to which is given by a spring or otherwise; and the invention relates especially to improved means for doffing or discharging the check rower line at the ends of rows; to improved means for transmitting to the seed-cup wheels intermittent revolutions in one direction, from such oscillating or rocking motion of the rock-shaft; and further especially relates to improvements in the discharge valve at the lower end of the seed-tube, and means for operating it; to structural features of the seed-cup wheel, and its gear connection with the rock-shaft; and to other constructions and combinations hereinafter described, and these improvements have for their object the production of an efficient planting machine, and which while structurally strong and durable will be efficient and simple in operation and economic 40 of manufacture; and the invention consists in constructions and combinations intended to accomplish these objects, and which are hereinafter described, and are summarized in the claims hereto appended.

45 In the accompanying drawings mechanism is shown embodying the constructive forms of, and showing the mutual relationship and combination of the parts forming the subject matter of my improvements embodied in the best way now known to me; obviously, however, some of these improvements may be

used without the others, and in planters differing in class or type, in construction, and in organization from the part of a planter shown by said drawings, and in which the 55 improvements are incorporated.

In said drawings:—Figure 1 is a top plan of the forward part or frame of an ordinary planter, embodying my improvements; Fig. 2, a perspective of the check rower line doffer, 60 with said line in operating place thereon; Fig. 3, a side elevation of the parts shown at Fig. 2; Fig. 4, a perspective of the parts shown at Fig. 2, with the doffer turned to force the check-rower line out of the pulley; 65 Fig. 5, a perspective of the doffer alone; Fig. 6, a sectional elevation, in the line 6, 6, in Fig. 4; Fig. 7, a side elevation of a seed-box, check-rower line, guide pulleys, and doffer; Fig. 8, a top plan of the parts shown at Fig. 7, and other adjacent parts. In this figure the seed-box is shown with its lid or cover removed, and with the cap-plate for the seed-cup wheel also removed; Fig. 9, a plan of the seed-cup wheel, including its separable central 75 part, and annular disk part, inverted; Fig. 10, a plan of the removable central part of the seed-cup wheel, inverted; Fig. 11, a plan of the removable outer or annular disk part of the seed-cup wheel, inverted; Fig. 11', a 80 side elevation of the central part of the seed-cup wheel, and the bevel pinion on rock-shaft in gear therewith, and section of rock-shaft; Fig. 12, a central sectional elevation of part of a seed-box, the dropping mechanism 85 therein without the cut-off, the seed-tube, and lower valve with part of its actuating mechanism; Fig. 13, a side elevation of a seed-box, part of a seed-tube, and part of the mechanism for transmitting motion from the 90 rock shaft, (shown in section,) to the seed-cup wheel; Fig. 14, a side elevation of the parts shown at Fig. 13, without the guard r^2 ; Fig. 15, a side elevation of the parts shown at Fig. 14, but in different relative positions 95 from what shown at said figure; Fig. 16, a sectional elevation in the seed-box, and dropping mechanism therein, substantially in line 16, 16, in Fig. 8; Fig. 17, a perspective of the parts shown at Figs. 14 and 15, but in different relative positions from what shown at said figures; Fig. 18, a top plan of the seed-

box, without the dropping mechanism, and broken away to show the rock-shaft and other parts beneath; Fig. 19, an elevation of the rock-shaft and mechanism for imparting movement therefrom to the seed-cup wheel; Fig. 20, an elevation of the foot pedal, sectional elevation of rock-shaft, and mechanism for transmitting motion from the foot pedal to the rock-shaft, in line 22, 22, in Fig. 21; Fig. 21, a rear elevation of the coupling of the rock-shaft, and link rod, which extends to the foot pedal; Fig. 22, an elevation of same parts shown at Fig. 20, and in line 22, 22, in Fig. 21, the dot lines showing the parts in different relative positions from what shown by the dot lines in Fig. 20.

The different figures of the drawings are made to different scales, and the same reference letters are used in each of said figures to designate the same parts.

To show the mutual relationship of my improvements to each other, and one way of mounting them on a corn-planter, I have shown in the drawings the forward part, A, of a planter, including the runners B, seed-tubes C, seed boxes D, transverse bar D', and frame bar D². The bar D' has its ends extended laterally, beyond the seed-boxes, and has at each end a cross bar or head d fixed thereto and stayed by braces d'. A rock-shaft E extends across the planter and has bearings in the seed-tubes through which it passes, and in brackets d² which are fixed to and pendent from the heads d. It will be evident, however, that the improvements shown, described, and herein claimed may be incorporated in planters of different construction, different organization, and different type or class from the part planter shown.

The seed-cup wheel G is formed in two parts, a central part G' and outer annular disk part G². The part G² has an ordinary circular series of seed-cups, g, with annular flanges g³ at their lower sides. An annular flange g³ also surrounds the central opening g⁸ in the disk G², and has recesses g⁴ therein, one on a radial line between each seed-cup and the one next to it. The part G' is a bevel pinion, with larger cogs g⁵ arranged alternately with smaller cogs g⁶. The larger cogs g⁵ extend radially from the body part of the pinion G', see Fig. 10, and fit the recesses g⁴ in the flange g³, see Fig. 9, and hold the parts G', G², of the seed-cup wheel so that they revolve together, and in such manner that they can be easily and quickly put together in proper relative positions, and disks G² with different sized seed-cups be readily substituted when desired. Each seed-cup wheel revolves on a pendent pivot stud g⁷ which projects centrally of and from the pinion G', and is journaled in a bearing g⁸ in a plate g⁹ which projects inwardly from one side of the central opening g¹⁰ in the seed-box bottom. The outer ends of the cogs g⁵ rest and slide upon the wall of the opening g¹⁰ in the seed-box bottom, and the annular flanges g³

rest and slide on said bottom, and thus support and steady the seed-cup wheel in its revolutions.

Beneath one side of each seed-cup-wheel a bevel pinion e is mounted on the rock-shaft E, as hereinafter described. The pinions e each have cogs e' in pairs, with narrower interdental spaces e² between the two cogs of each pair and broader interdental spaces e³ between the pairs of cogs e'. The smaller cogs g⁶ of the bevel pinion G' are adapted to act in the counterpart narrow spaces e² between the two cogs e' of each pair, and the larger cogs g⁵ are adapted to act in the larger counterpart spaces e³, as shown at Fig. 11'. When the seed cup wheel is removed from the seed-box for any purpose, it can be easily, quickly and properly replaced relatively to the drive pinion e, to cause the seed-cups as they are revolved in their circular orbit, to register or coincide successively with the opening d³ in the seed-box bottom, as herein-after described, by simply replacing it in such position that the cogs g⁵, g⁶, will engage with the counterpart spaces in the bevel pinion e as hereinbefore described.

The rock shaft E is given a partial rotation in the direction shown by the arrow at Fig. 13, by means of one of the forked levers e⁴ coming in contact with a tappet h on the check-rower line H, and being tripped or swung rearwardly thereby, to give such motion to the rock-shaft. The forked levers, as is common, are each mounted loosely on the rock-shaft E, and when either forked lever is swung rearwardly it acts upon a lug h' which is fixed to the rock-shaft, and thus gives motion in one direction to the rock-shaft, and the tappet then escaping from the rearwardly inclined fork and thus releasing said fork, a spring J, as hereinbefore described, returns the rock shaft or gives it a reverse motion, and the lug h' acting on the forked lever returns it to its normal position and ready for action by contact with the next succeeding tappet. When one forked lever is being thus acted on, the other remains inactive, as the lug h' next to it, swings away from it when acted on through the rock-shaft by a tappet, and swings back to it when acted on by the spring J.

Each bevel pinion e hereinbefore referred to, is fixed to one end of a sleeve K, which is loosely mounted on the shaft E, and has fixed to its other end a wheel M, having teeth m, whereby the pinion e and wheel M on each sleeve K revolve simultaneously with each other. The sleeves K are located, as shown at Fig. 16, each with the toothed wheel M which it carries, exterior to and preferably on the side of the seed-box toward the center of the planter. Adjacent to one side of each toothed wheel M an arm N is bolted and fixed to the shaft E. A pawl n is pivotally connected with the outer end of the arm N, in such manner that the lower end of said pawl hangs loosely over the wheel M, and is prevented from being thrown back out of its working

position by a lug n' that projects over it from the end of the arm N. Another arm projects from the arm N, and is bent laterally to form a trip n^2 which extends across the periphery 5 of the wheel M. Another arm n^3 projects from the arm N, and has its outer end formed into a hook, with which the lower end of the spring J is engaged, the upper end of said spring being fixed to the seed-box. The arms 10 N, n^3 , and trip n^2 are preferably integral, and fixed as before stated to the rock-shaft, to move therewith, but they may be separate parts, and be fixed separately to the rock-shaft, so that they have simultaneous 15 movements with said shaft. A plate R, bolted to the side of the seed-box has the outer ends of detents r , r' , pivoted thereto, which detents project toward each other and are held by their own gravity in contact with the upper 20 part of the wheel M, except when one of them is raised therefrom, as hereinafter described. The detents r , r' , are preferably located on the inner side of the plate R, and the pawl n and arm N on the outer side of said plate, which thereby acts to prevent them interfering with each other, see Fig. 16. A bracket or guard r^2 is bolted to the plate R at its upper end, extends over and protects the parts between it and the seed-box, and 25 has a bearing r^3 at its lower end for the shaft E.

Assuming the parts shown at Figs. 13 and 14 to be in their normal positions there shown, and the forked levers and other parts to be in their normal positions shown at Figs. 1, 7 30 and 8 by full lines, and a forked lever to have been tripped or swung rearwardly by contact with a tappet h, as shown by dot lines at Fig. 7, and to have given a partial rotation to the rock-shaft E, in the direction shown by the 35 arrow at Fig. 13, such movement of the rock-shaft will by means of the arm N, carry the pawl n to the position shown at Fig. 15, and said pawl being in contact with one of the cogs m will force the wheel M and pinion e 40 around to the positions shown at Fig. 15, and this partial rotation of the pinion e will impart to the seed-cup wheel a partial revolution and bring one of its seed-cups beneath the cut-off where it will register with the aperture d^3 in the seed-box bottom and deliver 45 its contained charge of seed therethrough and to the seed duct c' in the seed-tube. When the wheel M is partially rotated as last 50 described, the trip n^2 will be carried from beneath the detent or detent pawl r' and permit said detent to drop with its end in advance of the tooth m next succeeding the one last acted on by the pawl n, see Fig. 15, to arrest the further forward movement of the 55 wheel M and seed-cup wheel, and at the same time the detent r will fall from the cog m which supported it, and with its point in rear of the same cog, and serve to restrain the wheel M, pinion e and seed-cup wheel from 60 any backward movements that might arise from the backward movement of the arms N, n^3 and trip n^2 from any jarring or jolting of

the planter, or from any other accidental cause.

At Fig. 17 the last described full forward 70 movements of the parts are shown as only partly executed, the detent r still sustained on the cog in rear of which it falls, and the detent r' yet sustained above the cog m by the trip n^2 .

After the full forward movements hereinbefore described, of the rock-shaft, arm N, wheel M, sleeve K, pinion e, and seed-cup wheel, the spring J acts, through the hook arm n^3 on the shaft E, to rock said shaft in a 80 reverse direction to that last described, and thereby return the arm N, and trip n^2 and arm n^3 to the positions shown at Figs. 13 and 14, while the wheel M, sleeve K, pinion e and seed-cup wheel remain stationary. The trip 85 arm n^2 in making the return movement last described, comes in contact with the detent r' and trips it, or raises it and holds it out of contact with the tooth m with which it was last engaged, as shown at Figs. 13 and 14, and in 90 position for permitting another partial rotation forwardly of the rock-shaft, arms N, n^3 , trip arm n^2 , sleeve K, pinion e, and seed-cup wheel, as and for the purposes hereinbefore described.

It will be seen from the foregoing that the oscillating movement of the rock-shaft E in one direction on its axis, and given to it by a forked lever, will by means of the instrumentalities described, impart a partial revolution 100 to the seed-cup wheel, and that a reverse movement of the rock-shaft, given it by the spring, does not act upon the seed-cup wheel, and hence that the seed-cup wheel receives, through the instrumentalities described, an 105 intermittent revolution, or is intermittently revolved in one direction by the oscillatory or rocking movements of the rock shaft, for the purpose of bringing the seed-cups of its circular series in succession over the discharge opening d^3 , for the delivery of their contained seed to the seed-duct c'.

The seed-tube (see Fig. 12) has in addition to its ordinary seed-duct c', a chamber c^2 in front of and separated therefrom by a partition c^3 which terminates at its lower end a short distance above the lower end of the seed-tube. The discharging valve S is located below the lower end of the partition c^3 , and is there pivoted at s to the side walls of 120 the seed-tube. The valve S has a straight arm s' projecting tangentially from its center, and a curved arm s^2 , also at a tangent to its center, and having at its outer end an arc-shaped arm s^3 , with a curve concentric with 125 the axis of oscillation of the valve. The arms s', s^2 and one end of the arm s^3 form the sides of a U-shaped pocket or seed-cup s^4 . An arm s^5 projects from the valve S, and is pivotally connected at its outer end with the lower end 130 of a link or connecting rod T, the upper end of which is pivotally connected with a crank-arm s^6 which is fixed to the shaft E beneath the seed-box and within the chamber c^2 . (See

Fig. 12.) The arms of the valve S are of such width as to extend across the seed-duct c'. The normal position of the valve S is shown by full lines at Fig. 12.

- 5 When the valve S is swung into the position shown by dot lines at Fig. 12, to discharge the seed contained in the seed-cup s⁴, the arm s³ will, as shown, at the same time be brought beneath the lower end of the seed-duct c' to 10 close it, and to receive on its outer concave, now upper side the charge of seed which is dropped at the same time that the valve S discharged seed from the seed-cup s⁴ as last described, and when the spring J then gives 15 the reverse or return movement to the rock-shaft, while the seed-cup wheel is unmoved and stationary, the valve S will be swung back to its normal position shown by full lines, and in so swinging, the seed contained on the arm s³ will be scraped backwardly and drop into the seed-cup s⁴ ready for discharge by the 20 next swing of the valve S into the dot line position, as hereinbefore described, and ready to receive on the upper concave side of the arm s³ the charge of seed delivered by the seed-cup wheel at the simultaneous movement thereof. The arm s³ closes the lower end of the seed-duct c' so quickly when the valve S 25 swings to discharge seed from the seed-cup s⁴, that all seed dropping toward it, at the same time, will be received on the arm s³ and thus prevents all dribbling of seed in the row. When the rock-shaft E is given an oscillating motion, as hereinbefore described, to impart a 30 movement to the seed-cup wheel, the crank arm s⁶ will be turned into the position shown by full lines at Fig. 18, and by dot lines at Fig. 12, and in swinging into such position will by means of the rod T turn or swing the 35 valve S into the position shown by dot lines at Fig. 12, and in swinging into said position the velocity of the valve will be controlled by the rate of speed of the planter,—the greater the rate of speed of the planter in its 40 line of travel, the greater the velocity of the valve S, hence the valve not only throwing its contained charges of seed downwardly, but also rearwardly, will deposit them uniformly in the soil, and not, as is the case with ordinary planters, deposit the seed too far ahead when the planter moves with greater velocity, and too far back when it moves with diminished velocity. The greater the rate of speed 45 of the planter, the greater the velocity of my improved valve S, and hence the charges of seed will be thrown rearwardly with a force proportioned to that with which they are thrown forwardly by the forward motion of the planter, and be dropped to their places in the 50 ground with the same regularity as if all of the forward movements of the planter were at a uniform rate of speed.

In using a check-row planter with seeding devices operated by a check-rower line, it is 65 not convenient nor always practical to stretch said line for finishing-rows, or other very short rows that may be to plant, and in such

cases it is desirable to provide means for operating the rock-shaft E, by which the driver can operate it. Such means are shown partly 70 at Fig. 1, and fully at Figs. 20, 21 and 22, as I prefer for the purpose, and which are not claimed herein, as they are claimed in an application, Serial No. 420,959, prepared of even date herewith and filed February 10, 1892. 75 Such means consist in foot pedals V, hinged at their forward ends at v to brackets v' which are fixed to the bar D' and pivotally connected at their rear ends, each, to one end of a link rod v², the other end of which is pivotally connected at w with ears w' which project from an arm or tappet w² of a stirrup W. Arms w³ also project from the tappet w², and are loosely journaled on the shaft E. An arm W' made in two parts w⁴ having 80 confronting grooves which fit over the rock-shaft is fixed thereto between the arms w³ by a bolt w⁵ which fixes the parts w⁴ to each other and to the rock-shaft. The arm W' serves as a keeper to hold the stirrup W 85 against movement lengthwise of the rock shaft E, while permitting it to oscillate thereon. When the foot pedals, or either of them is swung downwardly, as shown by dotted lines at Fig. 22, the tappet w² will come in 90 contact with the outer end of the arm W' and carry it around to the position shown by dotted lines at same figure and thereby give a partial rotation to the rock-shaft to an extent limited by the outer ends of the brackets v', 95 to operate the seed-cup wheels, as hereinbefore described in reference to the operation of the rock-shaft by the forked levers. The foot pressure being then removed from the foot pedal, the spring J will give a reverse 100 movement to the rock-shaft as hereinbefore described, and restore the foot pedals, the stirrups W and arms W' again to their normal positions, and ready for a repetition of 105 the same movements and results.

When the stirrups W, arms W', link rods v² and foot pedals V are turned into the relative positions shown by dot lines at Fig. 20, these parts will sustain themselves in such positions, and permit of the rock-shaft being 110 oscillated automatically by the check-rower line and intermediate devices gearing it with the rock-shaft, and by the spring, without any motion being given to the foot pedals, which remain stationary, until again needed 115 for planting the short rows.

The cap plate X over each seed-cup wheel is of ordinary construction, having an ordinary annular opening x, coincident with the circular series of seed-cups g. No cut-off is 120 shown in the drawings, and any ordinary or desired cut-off may be used.

The forward guide pulleys Y are each journaled on a bracket y, which is fixed to a head d as hereinafter described. The rear guide 125 pulleys y' are journaled on short journals which are fixed to said head. These guide pulleys for the check-rower line, are of ordinary construction and may be mounted as 130

described, or in any other way that will admit of the use of my improved check-rower line doffer Z, as hereinafter described.

The doffer Z consists of a U-shaped main portion, the upper limb z of which is shorter than the lower limb z' in order to incline the limb connecting bar z², from a right angle to said limbs, as shown. One side of the limb z' is extended outwardly, upwardly and laterally thereof, to form a guide finger z³ for the check-rower line. The limb z' is journaled (see Fig. 6) on a stud z⁴ which projects from the bracket y, through which stud and bracket a bolt z⁵ passes, on which the pulley Y and upper limb z of the doffer are journaled. The upper limb z has a recess in which the nut on the upper end of the bolt z⁵ rests, to facilitate the passage of the check rower line thereover, as hereinafter described. A lug z⁶ projects from the end of the limb z', and is turned downwardly over the outer rounded end of the bracket y, (see Figs. 4 and 6,) to engage with a shoulder z⁷ on said bracket, to limit the movement of the doffer when it is swung into position for retaining the check-rower line on the guide pulley, and to engage with a shoulder z⁸ on the bracket when the doffer is swung to discharge or doff the check-rower line from the guide pulleys and forked lever.

At Figs. 1, 2, 3, 7 and 8 the doffer Z is shown in the position it occupies when the check-row chain H is in place on the guide pulleys Y, y', and in which position the bent finger z³ assists in retaining the check rower line H. The doffer is held in the position just described by contact of the lugs z⁶, z⁷, and by a rod z⁹ which is connected at one end with the arm z', and which passes through an eye z¹⁰ on the seed-box, and has a shoulder z¹¹, (see Fig. 7,) which is engaged with said eye to lock and hold the doffer in place. When it is desired to doff or free the check-rower line from the planter to turn it around at the end of rows, the catch or shoulder z¹¹ is released from the eye z¹⁰ by raising the rod z⁹. Then by pulling the rod z⁹ the doffer will be swung around until its lug z⁶ will come in contact with the lug z⁸, as shown at Fig. 4. In swinging as last described, the inclined bar z² will force the check-rower line out of the groove in the pulley Y, and the lateral pull of the line will then draw it up the inclined bar z² and over the pulley Y, at the same time lifting it sufficiently to free it of the forked lever, and the horizontal pulleys y' will then permit of its escape entirely from the planter. When the planter is turned around, the check-rower line is placed over the doffer, the doffer then turned into position to engage the line with the pulleys, and the catch z¹¹ then engaged again with the eye z¹⁰, to hold the doffer in position for planting operations.

Parts of the corn planting machine hereinbefore described, and shown in the drawings herewith, are made the subject matter of

claims in the application for Letters Patent hereinbefore referred to, and pending concurrently with this application, and hence are not claimed herein.

What I claim as new, and desire to secure by Letters Patent herein, is—

1. In a corn-planter, in combination, substantially as hereinbefore described, a seed-cup wheel having a gear wheel, a rock-shaft, a sleeve journaled on said shaft and having a gear wheel at one end in gear with the gear wheel of the seed-cup wheel, and a toothed wheel at its other end, and an arm fixed to the rock-shaft and provided with a pawl adapted to act on the toothed wheel and thereby on the sleeve and gear-wheels, to operate the seed-cup wheel.

2. In a corn-planter, in combination, substantially as hereinbefore described, a seed-cup wheel having a gear wheel, a rock-shaft, a sleeve loosely journaled thereon, provided at one end with a gear wheel in gear with the gear wheel of the seed-cup wheel, and at its other end with a toothed wheel, and means for transmitting intermittent rotary motion in one direction to said toothed wheel, sleeve, and gear wheel, and thereby similar motion to the seed-cup wheel, substantially as described.

3. In a corn-planter, in combination, substantially as hereinbefore described, a seed-cup wheel having a gear wheel, a rock-shaft, a sleeve loosely journaled on said rock-shaft and provided at one end with a toothed wheel, and at its other end with a gear wheel in gear with the gear wheel of the seed cup wheel, an arm fixed to the rock-shaft and provided with a pawl for giving movements to the toothed wheel, in one direction, and a detent for preventing backward or reverse movement thereof, substantially as described.

4. In a corn-planter, in combination, substantially as hereinbefore described, a seed-cup wheel having a gear wheel, a rock-shaft, a sleeve loosely journaled on said rock-shaft and provided at one end with a toothed wheel, and at its other end with a gear wheel in gear with the gear wheel of the seed-cup wheel, an arm fixed to the rock-shaft and provided with a pawl for giving movements in one direction to the toothed wheel and seed-cup wheel, and detents for arresting forward movement of, and detaining against forward or backward movement of said toothed wheel substantially as described.

5. In a corn planter, in combination, substantially as hereinbefore described, a seed-cup wheel having a gear wheel, a rock-shaft, a sleeve loosely journaled on said rock-shaft and provided at one end with a toothed wheel, and at its other end with a gear wheel in gear with the gear wheel of the seed-cup wheel, an arm fixed to the rock shaft and provided with a pawl for giving movements in one direction to the toothed wheel and seed-cup wheel, detents for arresting forward movements of, and detaining against forward or backward move-

ment of said toothed wheel, and a trip arm fixed to the rock-shaft for lifting one of said detents substantially as described.

6. In a corn planter, in combination substantially as hereinbefore described, a seed-cup wheel having a gear wheel, a rock-shaft with forked levers adapted for operation by a check-rower line, a sleeve loosely journaled on said rock-shaft and provided at one end 10 with a toothed wheel, and at its other end with a gear wheel in gear with the gear wheel of the seed-cup wheel, an arm fixed to the rock-shaft, and provided with a pawl for giving movements in one direction to the toothed wheel, 15 gear wheel and seed-cup wheel, detents for arresting forward movements of and detaining against forward or backward movement of said toothed wheel and seed-cup wheel, a trip arm fixed to the rock-shaft, for lifting one 20 of said detents, and a spring adapted to act on the rock-shaft through an arm fixed thereto, to give it alternating, reverse movements with its movements given by the check-rower line, and without imparting movement to the 25 seed-cup wheels.

7. In a corn-planter, in combination, substantially as hereinbefore described, a seed-cup wheel having a gear wheel, a rock-shaft with forked levers which give it partial rotations in one direction from movements given the forked levers by a check-rower line, a sleeve having a toothed wheel M and gear wheel e fixed thereto, arms N, n^3 and trip arm n^2 fixed to the rock-shaft, the arm N having 35 a pawl n , detents r, r' , and spring J , adapted to act on the arm n^3 to give reverse movements to the rock-shaft, without moving the seed-cup wheel.

8. In a corn-planter, in combination substantially as hereinbefore described, a seed-cup wheel having a gear wheel, a rock-shaft partially rotated in one direction by means of forked levers thereon coming in contact with the tappets on a check-rower line, a sleeve 45 journaled on said rock-shaft and having fixed thereto a toothed wheel at one of its ends and a gear wheel at its other end which gears with the gear wheel on the seed-cup wheel, an arm fixed to the rock-shaft and provided with 50 a pawl which acts on the toothed wheel, to impart intermittent revolutions in one direction to the seed-cup wheel, and an arm also fixed to the rock-shaft and adapted to receive motion from a spring to give reverse movements 55 to the rock-shaft without moving the seed-cup wheels.

9. In a corn-planter, in combination, substantially as hereinbefore described, a pivoted discharge valve located at the lower end of 60 the seed-tube, and having arms or plates s^1, s^2, s^3 , which form a seed-pocket or cup adapted to receive the seed, and a crank arm s^5 which is connected by a link rod T with a crank-arm s^6 on the rock-shaft, which is operated by a check-rower line, whereby the 65 valve will discharge the seed with a down-

ward and backward velocity proportioned to the rate of speed of the planter.

10. In a corn-planter, in combination, substantially as hereinbefore described, a pivoted 70 discharge valve having a curved arm or wing s^3 adapted to receive seed on its outer side as it is delivered from the seed-cup wheel, a front wall to the seed-duct, adapted to scrape the seed therefrom as the valve is swung by 75 a spring, and a seed cup or pocket s^4 adapted to receive the seed as it is removed and drops from the arm s^3 .

11. In a corn-planter, in combination, substantially as hereinbefore described, a pivoted 80 discharging valve S , having wings or plates s^1, s^2, s^3 , located in such manner that the curved wing s^3 swings in contact with a scraping surface above it, and having an arm s^5 connected by a rod T with an arm s^6 on the rock-shaft 85 E , with forked levers thereon, which are operated by a check-rower line, whereby the valve is swung to discharge seed by means of the check-rower line, and in a reverse direction by the spring J . 90

12. In a corn planter, in combination substantially as described, a seed tube, with a wall shortened up at its lower end, an oscillating discharge valve having a seed pocket s^4 , and an arm, as s^3 , and a rod connecting 95 said discharge valve with an arm on the rock shaft of the planter, all constructed and arranged in such manner that the same seed pocket discharges each and every discharge of seed, and receives one charge of seed direct from the seed duct, and the alternate charges as swept from the outer side of the arm s^3 , by the lower end of the shortened wall 100 of the seed duct.

13. In a corn-planter, in combination, substantially as hereinbefore described, an intermittently revolved seed-cup wheel, a pivoted valve S with a curved arm s^3 adapted to receive charges of seed on its outer side as delivered from said seed-cup wheel, and a cup 105 or pocket s^4 adapted to receive the seed from the curved arm s^3 when said valve is swung to its normal position.

14. In a corn planter, the combination substantially as hereinbefore described, with a 115 wall at one side of the seed tube, shortened at its lower end, of an oscillating seed discharging valve located in the lower end of the seed tube, and having a pocket in its periphery, which receives seed direct and discharges it 120 at one back and forth swing of said valve, and a curved arm which receives seed on its outer surface at a swing of the valve in one direction, which seed is swept therefrom by the lower end of said shortened wall, and 125 into the seed cup at the next swing of the valve.

15. In a corn-planter, in combination substantially as described, a rock-shaft with forked levers, pulleys Y , check-rower line, and 130 doffer having arms z, z' , both pivotally connected at their ends with the bolt z^5 on which

said pulley rotates, connected with each other by a bar z^2 , and the arm z' extended to form a guard finger z^3 for the check-rower line.

16. In a corn-planter, in combination, substantially as described, a rock-shaft with forked levers, pulleys Y, check-rower line, and doffer having arms z, z' , both pivotally connected at their ends with the bolt z^5 on which said pulley rotates, and connected with each 10 other by an inclined bar z^2 , the arm z' extended to form a guard finger z^3 for the check-rower line, and having a lug z^6 adapted to engage with the lugs z^7, z^8 , for the purpose specified.
- 15 17. In combination substantially as herein-

before described, with a rock-shaft having forked levers, a pulley Y, and check-rower line, a doffer having arms z, z' , both pivotally connected at their ends with the bolt z^5 on which said pulley is journaled, and connected 20 with each other by an inclined bar z^2 , the arm z' extended to form a guard finger, and a rod z^9 with a shoulder z^{11} adapted to engage with an eye z^{10} , for the purpose specified.

In testimony whereof I affix my signature in 25 presence of two witnesses.

ABRAHAM ANDERSON.
